FRONT PANEL FOR A METER OR SIMILAR ARTICLE

Samuel S. Leotta, Hatboro, Pa., assignor to Minneapolis-Honeywell Regulator Company, Minneapolis, Minn., a corporation of Delaware

Filed Mar. 27, 1961, Ser. No. 64,496

Term of patent 14 years

(Cl. D26—1)

FIG. 1

FIG. 3

FIG. 2

FIG. 1 is a front, perspective view of a front panel for a meter or similar article, showing a new design;

FIG. 2 is a top plan view, to a reduced scale, the opposite side being substantially a mirror image thereof; and

FIG. 3 is a side elevational view thereof, to a reduced scale.

The design shows near the bottom of the panel electric lamp bulbs surrounded by circular rings.

The rear of the panel is conventional.

The broken line showing of the cabinet, dial and pointers appears for illustrative purposes only.

I claim:

The ornamental design for a front panel for a meter or similar article, substantially as shown and described.
